(No Model.)

J. WELLS.

EARTH AUGER.

No. 362,562.

Patented May 10, 1887.

UNITED STATES PATENT OFFICE.

JAMES WELLS, OF PARIS, ASSIGNOR OF ONE-HALF TO D. S. PRICE, OF
NORTH MIDDLETOWN, KENTUCKY.

EARTH-AUGER.

SPECIFICATION forming part of Letters Patent No. 362,562, dated May 10, 1887.

Application filed February 28, 1887. Serial No. 229,194. (No model.)

To all whom it may concern:

Be it known that I, JAMES WELLS, a citizen of the United States of America, residing at Paris, in the county of Bourbon and State 5 of Kentucky, have invented a new and useful Earth-Auger, of which the following is a specification.

My invention has relation to improvements in implements for boring into the soil, such as 10 making post-holes and similar excavations; and the object is to provide an implement of the class named which may be readily and certainly adjusted to bore holes of different diameters and in which adjustment the points 15 of the blades may be set in proper cutting position notwithstanding the enlargement or reduction of the diameter of the bore the implement may be set to.

With these objects in view my invention 20 consists in the novel construction of parts and their combination, as will be hereinafter more fully described, and especially as will be specifically pointed out in the claim made hereto, as required by statute.

25 I have fully illustrated my improvements in the accompanying drawings, wherein—

Figure 1 is a perspective view of the implement. Fig. 2 is a view of the handle and head with the adjustable plates, and Fig. 3 is a view 30 of one of the blades with the head-piece fixed thereto.

In the drawings similar parts are identified by like notations, and reference being thereto had, the letter A designates the stem of the 35 auger provided with a handle or cross-bar, 1, fixed to its upper end, and formed with a rectangular head, 2, at its lower end, to receive the sliding plates carrying the angular plates, as hereinafter described, to which the blades 40 are attached.

The letter B designates sliding plates. These are of such length as to meet the size of the tool to which they may be applied, and, also, of such length that when arranged in position 45 on the rectangular head the ends of the upper set shall set across the ends of the lower set, and thus keep them all in horizontal position and from turning on the fastening means. Each of these sliding plates is formed with a slot, 50 3, arranged in the direction of its length, and is adjustably held to the head of the stem by set-screws, 4, projected through the

said slots into the body of the head. These sliding plates are adjustable, as indicated, in horizontal direction, thereby affording means 55 for setting the blades to any desired cut.

The letter C designates angular plates. These are formed with the part 5 to set against the face of the sliding plates, and are secured thereto by set-screws 6. The other and outer arm 60 of these angular plates is struck at right angles to the part attached to the sliding plates, and has its outer face formed to fit the inner face of the upper end of the cutting-blades. As will be seen, the attachment of these angular 65 plates to the sliding plates permits them to be turned on the set-screws, holding them to the sliding plates in a vertical movement in the arc of a circle, and thus carry the points of the blades inward or outward.

The letter D designates the cutting-blades. These are formed with their upper ends to set 70 against the outer and angular arms of the angular plates, and are secured thereto by means of bolts or screws 8. From the part 75 held against the arm of the angular plate the blades are bent inward, so that the points of the number shall almost meet; and the outer faces of the blades are somewhat rounded, and the inner faces thereof inclined in cross-section in the direction of the movement and are brought to a cutting-edge, as shown in the drawings. The stem of the auger and the 80 sliding plates and the angular plates are made of iron, and the cutting-blades of steel.

It will be perceived from the foregoing that by sliding the sliding plates on their set-screws and clamping them in the desired place, the diameter of the bore is fixed as wanted; and that this being determined, the blades may be 85 turned on the set-screws of the angular plates in the parts secured to the sliding plates, and the points of the blades thus brought in proper contiguity at the center, notwithstanding the slides on the head of the handle may be set 90 for a larger bore. If the implement is to be adjusted from a greater to a less bore, the slides are adjusted, as heretofore stated, on the set-screws to determine the diameter, and then the points of the blades are drawn outward 95 and the set-screws of the angle-plates fastened.

What I claim as my invention, and desire to secure by Letters Patent, is—

The herein-described improved earth-auger,

comprising the handle formed with a rectangular head, 2, at its lower end, the sliding plates B, formed with longitudinally-arranged slots, and adjustably secured to the faces of the said head by set-screws projected through the said slots, angular plates C, having one arm thereof secured to said sliding plates to move vertically in the arc of a circle, and the cutting-blades D, having their upper ends se-

cured to the outer arms of the angular plates, to the extent as set forth.

In witness whereof I have hereunto set my hand in the presence of two attesting witnesses.

JAMES WELLS.

Attest:

ROBT. C. TALBOTT,

JAMES Q. HORTON.
